UNITED STATES PATENT OFFICE.

JETHRO J. RICE, OF GRAND RAPIDS, MICHIGAN.

DESIGN FOR A DRESSING-CASE, &c.

SPECIFICATION forming part of Design No. 23,926, dated January 1, 1895.

Application filed September 17, 1894. Serial No. 523,284. Term of patent 7 years.

To all whom it may concern:

Be it known that I, JETHRO J. RICE, a citizen of the United States, residing at Grand Rapids, in the county of Kent and State of Michigan, have invented and produced a new and original Design for Dressing-Cases and Analogous Articles of Furniture, of which the following is a specification, reference being had to the accompanying drawing, in which I have illustrated the design in connection with a dressing-case and in which the figure is a perspective view.

The leading feature of my design consists in a dressing case, the ends of the body whereof are formed with, or in a double or reverse ogee curve, the concave portion of said curve being at the rear and the convex portion at the front of the case.

In the said drawing the reference-numeral

1 indicates a dressing case the ends of the body whereof are formed with or in a double or reverse ogee curve, the concave portion 2 of said curve being at or toward the rear of the case and the convex portion 3, at or toward the front of the case.

An ornamental border 4, 5, is arranged at the upper and lower extremities of the double or reverse ogee curve.

What I claim is—

The design for a dressing case or analogous article of furniture, herein shown and described.

In witness whereof I have hereunto set my hand and seal in the presence of two witnesses.

JETHRO J. RICE. [L. S.]

Witnesses:

ARTHUR C. DENISON,
CHRISTOPHER HONDELINK.
